UNITED STATES PATENT OFFICE.

WILLIAM A. WEIGHTMAN AND CHARLES H. NITSCH, OF PHILADELPHIA, PENNSYLVANIA, ASSIGNEES TO STOKES & SMITH COMPANY, OF SUMMERDALE, PENNSYLVANIA, A CORPORATION OF PENNSYLVANIA.

COATING-MACHINE-CLEANING APPARATUS.

Application filed April 2, 1921. Serial No. 458,157.

To all whom it may concern:

Be it known that we, WILLIAM A. WEIGHTMAN and CHARLES H. NITSCH, citizens of the United States, and residents of Philadelphia, 5 in the county of Philadelphia and State of Pennsylvania, have invented certain new and useful Improvements in Coating-Machine-Cleaning Apparatus, of which the following is a specification.

10 Our invention relates to improvements in coating machines, and is particularly directed to an improved construction for readily cleaning parts of the machine which carry the coating material.

15 Our invention is primarily designed for application to the type of coating machine in which the fluid coating material is transferred from a reservoir by means of contacting rollers to one side of the coated article, 20 which passes over a roller. In the form disclosed it is employed on a coating machine of the type disclosed in the United States patent to Morrison No. 1,331,460, in which the applying roller is provided with a number 25 of circumferential grooves to accommodate stripper fingers which break the engagement between the sheet being coated and the roll. In the course of operation these grooves and the stripping mechanism, 30 as well as other parts of the coating apparatus to a lesser extent, gradually become more or less gummed up with the adhesive employed for coating. The cleaning which is necessary at regular intervals is more or 35 less tedious and time-consuming, owing to the difficulty in gaining access to all the various corners and recesses of the parts.

A principal object of our invention is to provide means for readily and rapidly cleaning coating apparatus by means which is in 40 part automatic, avoiding the necessity for manual cleaning of the various parts.

A further object is to provide means of this sort which will perform its function in 45 a comparatively short space of time, reducing stoppage of the machine for this purpose to a minimum, and which also may be conveniently manipulated.

In the preferred form, our invention is 50 applicable to the type of coating machine in which the coating fluid is heated by a water bath, as is the general practice in gluing machines; and a more specific object is to employ the water used for heating the

coating fluid as the medium for cleaning the 55 coating apparatus. A concomitant object is to provide a construction in which the heating water may be readily and rapidly applied to the parts to be cleaned.

Other objects and advantages of our invention will be apparent from the following description, taken in connection with the accompanying drawings, in which:

Figure 1 is a side elevation of coating apparatus embodying our invention in coating 65 position, the cleaning position being indicated in dotted lines, parts being broken away, and

Figure 2 is a similar view with the parts in position intermediate the coating and 70 cleaning positions, the latter position being indicated in dotted lines.

For convenience in following the detailed description, it may be noted that we preferably employ a pan for adhesive, movably 75 mounted on a trough carrying the hot water bath. When it is desired to clean the parts, the pan and trough are lowered away from the coating rollers, the pan is retracted to expose the water bath, and the trough containing the water is then elevated to bring the lowermost coating roller into the bath. The machine is then operated, carrying the hot water over the parts to be cleaned.

In machines of the type indicated, the 85 coating material 10 such as paste or glue, is retained in a pan 11 suitably supported so that the dipping roller 12 will extend into the fluid. The coating roller 13 in contact with dipping roller 12 receives the coating 90 fluid from the latter and transfers it to the article to be coated, such as a sheet of paper 14. In the particular machine illustrated, the coating roller 13 is provided with circumferential grooves 15 into which the 95 stripping and cleaning fingers 16 extend, the upper ends of the fingers stripping the paper from roll 13, while the lower ends of the fingers extend into the grooves to clean them, all as set forth in Patent No. 1,331,463. 100 It will of course be appreciated that these details of construction are purely illustrative, as our invention is equally applicable to a great variety of coating machine constructions employing coating rollers or 105 analogous elements.

The fluid 10 is maintained at a proper temperature by means of a suitable water

jacket heated in any desired way. The hot water 17 in the form illustrated is retained in a trough 18 upon which pan 11 rests, the pan dipping into the water 17. The water 5 may be heated by steam passing through the pipe coil 19 in trough 18.

Pan 11 is slidably mounted on trough 18, so that it may be slid rearwardly to a point where it is completely out of register with 10 the dipping roll 12. This may be conveniently accomplished by providing trough 18 with a flat edge 20 upon which the marginal lip 21 of the pan 11 rests, forming a tight connection but permitting the pan to 15 slide along the trough. In order to seal the water jacket tightly, we form pan 11 substantially shorter than trough 18, and provide the pan with an extension or hood 22 overlying the front of the trough and having 20 a marginal lip 23 in continuation of lip 21 on the pan 11 resting on edge 20 of the trough. A filling opening 24 for replenishing the water 17 may be provided in hood 22.

25 For convenience in sliding pan 11 away from the dipping roller 12, and to break any adhesion or strong frictional engagement between the trough edge 20 and lips 21 and 23, we may employ handles 25 30 pivotally mounted at 26 on the hood 22, the handles dropping out of the way against stops 27 on lip 23 when not in use. It will be understood that while for convenience only one side of the apparatus has been 35 illustrated, the opposite side is substantially identical therewith, and a handle 25 is preferably mounted at each side. When pan 11 is to be retracted, handles 25 swing upwardly against abutments 28 projecting at 40 each side of hood 22 as illustrated in Figure 2, so that the operator may readily lift the rear end of the pan and slide it forward free from excessive frictional engagement with the trough.

45 We provide means for readily lowering the trough and pan into position where the pan may be retracted without interference from the coating roller 12 or other parts of the coating apparatus. One convenient arrangement for this purpose is illustrated, including bell cranks 29 pivotally mounted at 50 30 on bracket 31 of the machine frame, the upper arms of the cranks being pivoted in clevises 32 on trough 18. The lower ends 55 of the cranks are connected by links 33, so that the trough 18 and pan 11 will maintain a substantially horizontal position while being lowered and raised. For shifting the trough and tank, we extend one of the cranks 29 to form a hand lever 34.

We also preferably provide means for locking the parts in position with the pan 11 elevated to the proper height for feeding adhesive to the dipping roll 12. For this purpose we may employ a latch including a dog 60

35 pivotally mounted on lever 34 and normally pressed by spring 36 into engagement with a notch 37 carried by extension 38 of the bracket 31. A thumb piece 39 on dog 35 provides convenient means for 70 releasing the latch when the pan and trough are to be lowered.

It will be understood that in the form shown we employ four bell cranks 29, two at each side of the bracket 31, each pair being connected by a link 33; and lever 34 is an extension of a bell crank at the rear of bracket 31.

75 We will now set forth the detailed operation of the device. The parts as shown 80 in Figure 1 in full lines are in coating position, where they remain during the normal running of the machine. When it is desired to clean the coating parts, the operator grasps lever 34, releasing the latch 85 by depressing dog 35 through manipulation of thumb piece 39, and raises lever 34, swinging the trough 18, pan 11, and connecting parts down to the level shown in full lines in Figure 2, the trough resting 90 on bracket 31. The operator then grasps handles 25, swinging them upwardly; and if necessary raising the rear end of the pan 11 slightly by engagement between the levers and abutments 28. The pan is then retracted to the position shown in full lines in Figure 2, exposing the water 17 immediately below dipping roller 12, and raised until the roller dips into the water. The normal operation of the machine will 100 then carry the heated water over rolls 12 and 13, into the grooves 15, over the contiguous portions of fingers 16, and onto such adjacent parts as may at any time be in contact with the elements which normally 105 carry the coating fluid. It has been found that by running the machine for a very short time in this way, these parts will be cleaned very thoroughly.

Owing to the fact that the level of water 110 17 may be normally slightly below that of the coating fluid 10, it may be desirable to swing trough 18 during the cleaning operation to a point slightly higher than its normal location during coating. This object is attained very simply by providing another notch 40 in the extension 38 of bracket 31, the lever 34 being forced downwardly until dog 35 engages notch 40 when the parts are in cleaning position.

115 To return the parts to coating position the operation above described is reversed. It will be apparent that while the operation has been set forth at some length, it may be performed with great rapidity, the elevation of lever 34, retraction of the pan by handles 25, and subsequent depression of lever 34 occupying but a fraction of a minute, the reverse operation consuming a similar space of time. Moreover, the water is 120 125 130

applied almost immediately to all of the parts requiring cleaning, and to no other parts of the machine; and this together with the employment of heated water, renders the process not only highly expeditious and efficient, but also free from splashing.

It will be apparent that numerous variations in the construction illustrated may be employed. For instance, our invention is not limited to the particular method of lowering and raising the trough and pan, nor to the particular construction and arrangement for retracting the pan preparatory to the cleaning operation. As a matter of fact, in the broad aspect of our invention, it is not necessarily limited to a water jacket pan, nor to the employment of the heated water from such jacket in the cleaning operation.

Furthermore, while we have described water as the cleaning fluid, it will be apparent that other fluids, either hot or cold, may be employed in a similar manner, depending largely upon the type of coating material which the machine employs.

We claim:

1. Cleaning apparatus for adhesive coating machines, comprising adhesive coating mechanism including a moving coating member contacting with other elements of said mechanism for transferring the adhesive thereto, and means for applying a supply of cleaning fluid to said member to be carried thereby to said elements for cleaning the latter.

2. Cleaning apparatus for adhesive coating machines, comprising coating mechanism including a roller for carrying coating fluid contacting with other elements of the coating mechanism for transferring the adhesive thereto, and means for applying a supply of cleaning fluid to said roller to be carried thereby to said elements for cleaning the latter.

3. Cleaning apparatus for adhesive coating machines, comprising coating mechanism including a roller for carrying coating fluid contacting with other elements of the coating mechanism for transferring the adhesive thereto, and means for applying a supply of cleaning fluid to said roller to be carried thereby to said elements for cleaning the latter, said means including a reservoir for the cleaning fluid movable into position to bring said fluid in contact with the roller surface.

4. Cleaning apparatus for coating machines, comprising coating mechanism including a moving coating member contacting with other elements of the coating mechanism, a reservoir for coating fluid into which said member normally dips, an open container for cleaning fluid, means whereby said reservoir may be shifted out of operative position, and means whereby the con-

tainer may be held in position where said member will dip into the cleaning fluid therein.

5. In a coating machine, coating mechanism, a reservoir for coating fluid normally located below the coating mechanism, a container for cleaning fluid, and means whereby said container may be substituted for said reservoir to supply cleaning fluid instead of coating fluid to said mechanism. 70

6. In a coating machine, coating mechanism, a reservoir for coating fluid, provisions for heating said fluid by means of a hot liquid, and means for applying said hot liquid to the coating mechanism for cleaning purposes. 80

7. Cleaning apparatus for coating machines including a reservoir for coating fluid, means for heating said fluid including a hot liquid and a container therefor adapted normally to maintain said liquid against the reservoir; and means for holding said container in position to supply the liquid to the coating mechanism for cleaning purposes after the reservoir has been shifted 90 from normal position.

8. Cleaning apparatus for coating machines, including a reservoir for coating fluid, a trough containing a cleaning liquid, said trough supporting the reservoir in operative position, means whereby the reservoir may be shifted along the trough into inoperative position, and means whereby the trough may thereafter be maintained in position to supply the liquid to the coating mechanism for cleaning purposes. 100

9. Cleaning apparatus for coating machines, including a container for cleaning liquid, a reservoir for coating fluid shiftably mounted on said container, means for supporting said container and reservoir in position to supply said fluid to the coating mechanism, and means whereby said container and reservoir may be shifted into position to supply said liquid directly from the container to said mechanism. 105

10. Cleaning apparatus for coating machines, including coating mechanism, a container for cleaning liquid therefor, and a reservoir for coating fluid slidably mounted on said container and extending downwardly thereinto, the portion of said reservoir extending into the container being shorter than the container in the direction of relative movement between container and reservoir, the construction being such that the reservoir may be slid along the container to expose a portion of the liquid in the latter without raising the reservoir out of the container. 115

11. In a coating machine, coating mechanism, a reservoir for coating fluid associated therewith and means for moving the reservoir into and out of cooperative association with the coating mechanism, the said 120 130

means including a holder for the reservoir, spaced crank arms movably supporting the holder an operating handle connected to the said crank arms for imparting motion there-
5 to and link means connecting the crank arms.

12. In a coating machine, coating mechanism, a reservoir for coating fluid located below the coating mechanism, and means
10 for moving the reservoir into and out of cooperative association with the coating mechanism, the said means including provisions for raising and lowering the reservoir and independent provisions for mov-
15 ing the same horizontally to and from the coating mechanism.

13. In a coating machine, coating mechanism, a reservoir for coating fluid located below the coating mechanism, means for
20 moving the reservoir into and out of cooperative association with the coating mechanism, the said means including provisions for raising and lowering the reservoir and

independent provisions for moving the same horizontally to and from the coating mechanism and means for limiting the motion of the reservoir in its horizontal movement. 25

14. In a coating machine, coating mechanism, a reservoir for coating fluid associated therewith and means for moving the reservoir into a plurality of positions into and out of cooperative association with the coating mechanism; the said means including a holder for the reservoir, spaced pairs of crank arms movably supporting the holder, 30 an operating handle connected to the said crank arms for imparting motion thereto, link means connecting a crank arm of one pair with a crank arm of another pair and means for locking the said holder in its plurality of positions. 35

Signed at Philadelphia, in the county of Philadelphia and State of Pennsylvania this 31st day of March, A. D. 1921.

WILLIAM A. WEIGHTMAN.
CHARLES H. NITSCH.
